(57) **CLAIM**

The ornamental design for a display screen or portion thereof with graphical user interface, as shown and described.

DESCRIPTION

The FIGURE depicts a display screen or portion thereof with graphical user interface, showing our new design.

The outermost broken lines show a display screen or portion thereof and form no part of the claimed design. The remaining broken lines within the FIGURE show portions of the graphical user interface which form no part of the claimed design.

The curvy break lines in the FIGURE illustrate a symbolic break in the horizontal dimension. The appearance of any portion of the design between the break lines forms no part of the claimed design. The symbolic break lines themselves form no part of the claimed design.
